FASTENER HOLDING DEVICE

Filed May 5, 1928

FIG. - 1.

FIG. - 2.

FIG. - 3.

K BY Andrew J. Neafie
HIS ATTORNEY

INVENTOR.

UNITED STATES PATENT OFFICE

ANDREW J. NEAFIE, OF MOUNTAIN LAKES, NEW JERSEY, ASSIGNOR TO INGERSOLL-RAND COMPANY, OF JERSEY CITY, NEW JERSEY, A CORPORATION OF NEW JERSEY

FASTENER-HOLDING DEVICE

Application filed May 5, 1928. Serial No. 275,393.

This invention relates to fastener holding devices, but more particularly to a fastener holding device adapted for attachment to a pneumatic hammer tool of the type employed for driving spikes and similar articles.

One object of the invention is to enable the hammer tool to be readily retained in striking relation with the spike unaffected by the vibration set up in the tool during its operation.

Other objects will be in part obvious and in part pointed out hereinafter.

In the drawings accompanying the specification and in which similar reference characters refer to similar parts,

Figure 1 is a side elevation of a pneumatic tool having the invention applied thereto,

Figure 2 is an enlarged detail elevation partly broken away of the front end of a pneumatic tool and the holding device, and

Figure 3 is a transverse view taken through Figure 2 on the line 3-3 looking in the direction indicated by the arrows.

Referring to the drawings, the invention is shown applied to a pneumatic tool having a cylinder A to the rearward end of which is secured a back head B by means of bolts C. The back head B is provided with a handle D adapted to be grasped by the operator for manipulating the tool and for applying pressure to the work during the operation of the tool. The parts so far described are shown merely for the purpose of illustrating a practical application of the invention and it is to be understood that the invention is not limited in its use to the particular type of tool shown.

To the front end of the cylinder A is secured a front head E which may be of a well known type to act as a guide for the forward portion of a hammer piston F. The piston F in this instance reciprocates through the front end of the front head E to deliver its blows directly against the work, such as a railroad spike G intended to be driven into a tie H for securing a rail J thereto.

Means such as side rods K are employed for securing the front head E to the cylinder A. Preferably springs L are disposed on the side rods to bear with one end on lugs O of

the front head and with their opposite ends against nuts P threaded on the side rods K to exert a constant tension for the purpose of maintaining the front head E firmly against the cylinder A.

In accordance with the present invention the side rods K are provided at their forward ends with extensions Q of somewhat smaller diameter than the body portions of the side rods for the reception of holding means such as will be hereinafter described in detail.

In driving spikes and similar articles with tools of the type illustrated a difficulty frequently encountered is that of maintaining the tool in striking relation with respect to the article intended to be driven. This is due partly to the small area of contact between the striking end of the piston F and the article, such as the spike G, and in part to the terrific vibration set up in the tool during its operation.

In order that the tool may be readily maintained in the correct position relatively to the spike a sleeve R is disposed on the front head E and said sleeve has a bore S adapted to slidably receive the forward portion of the front head. The bore S may be of any suitable size but is preferably of such diameter that the head of the spike will always be within the striking range of the piston F in any position which the tool may assume on the spike.

On opposite sides of the sleeve R are lugs U in which are formed apertures V to slidably receive the extensions Q of the side rods K. Nuts W are threaded on the forward end of the extensions Q to act as abutments for the sleeve and to limit the forward movement of the sleeve on the front head E. Preferably ribs X are formed on the sleeve R and on opposite sides of the apertures V to serve as guards for the forward extremities of the extensions Q and the nuts W.

In practice, whenever it is desired to drive a spike, the spike may be placed in substantially the correct position relatively to the rail J and the tool may then be seated on the spike and the piston F set in operation. After the spike has been properly started in

the tie H, the operator may apply pressure to the handle D and the spike will then be rapidly driven into the tie H to secure the rail J thereto.

As the head T of the spike G approaches the rail flange the front end of the sleeve R will contact with the flange of the rail and will be gradually pushed rearwardly on the front head E in accordance with the degree 10 of penetration of the spike into the tie. The front end of the sleeve however, will at all times be in engagement with the head of the spike, thus assuring the correct position of the piston F relatively to the spike and consequently increasing the efficiency of the 15 tool since the tool may be operated at maximum speed with the full assurance that every blow struck by the piston F will be effective.

I claim:

1. In a fastener holding device, the combination of a hammer tool having a cylinder and a front head, side rods for clamping the cylinder and the front head in assembled relationship, a hammer piston in the cylinder for delivering blows of impact, a sleeve 20 slideable on the front head for guiding a fastener during the driving thereof, lugs on the sleeve having apertures to receive the side rods, and nuts on the side rods for maintaining the sleeve on the front head.

2. In a fastener holding device, the combination of a hammer tool having a cylinder and a front head, spring pressed side rods for clamping the front head to the cylinder, 25 reduced extensions on the side rods, a hammer piston in the cylinder, a sleeve slideable on the front head for maintaining a fastener within the range of the blows of the piston, lugs on the sleeve having apertures to slideably receive the extensions, and nuts on the 30 extensions for limiting the forward movement of the sleeve relatively to the front head.

In testimony whereof I have signed this
45 specification.

ANDREW J. NEAFIE.
